UNITED STATES PATENT OFFICE.

PETER MACGREGOR, OF OTTAWA, ONTARIO, CANADA.

VERTICAL FILE.

947,218.

Specification of Letters Patent. Patented Jan. 18, 1910.

Application filed August 9, 1909. Serial No. 512,071.

To all whom it may concern:

Be it known that I, PETER MACGREGOR, of Ottawa, in the Province of Ontario, Canada, have invented certain new and useful 5 Improvements in Vertical Files, of which the following is a specification.

My invention relates to improvements in vertical files and the objects of my invention are to provide a file or envelop in which 10 papers may be filed vertically and such as may be conveniently placed on shelves and have their contents indexed by suitable indexes on the front or side thereof, further objects being to economize space in the storing 15 of the files, whereby, when not full, the sides will collapse together and occupy only an amount of room to correspond with the number of papers or documents inside. In its construction it includes a filing envelop 20 formed with two parallel sides and collapsible ends and bottom, the front end being formed of a narrow strip of stiff material adapted to receive indexing printing.

In the alternative form of the invention 25 a cover is provided for the top of the file and a stiffening member may be provided to hold the bottom in an extended position.

These and other features of the invention 30 are more fully described in the accompanying specification and drawings.

In the drawings, Figure 1 is a perspective view of the file. Fig. 2 is a transverse section through the same in collapsed position. Fig. 3 is a perspective view of an alternative 35 form of the invention. Fig. 4 is a horizontal section through the alternative form in collapsed position. Fig. 5 is a transverse section through the alternative form of the invention. Fig. 6 is the same view as Fig. 5 40 with the stiffening member inserted along the bottom of the file. Fig. 7 is a perspective view of the pivoted member for holding the file in extended position. Fig. 8 is a sectional detail on the line, 2-2, Fig. 3. Fig. 45 9 is a sectional detail on the line, 3-3, Fig. 3.

In the drawings, like figures of reference indicate corresponding parts in each figure.

The file, as will be seen from the drawings, is made in the form of an envelop with an open top. The two sides 10 and 11 extend parallel with each other and are formed of fairly stiff material, such as very heavy Manila paper, whereby they will 50 maintain their upright position when the

base is extended. Both the ends and bottom are made collapsible, as by bellows hinges or other means.

In all the forms, the bottom 12 is formed by a bellows hinge. In the form shown in Fig. 2, the rear end 12 is also formed by a bellows hinge. The front 14 of the file is formed by a strip of narrow stiff material, such as cardboard, connected at the edge 15 to the side 11, and at 16 to the opposite side, and is made collapsible by forming a crease 16' in the side a short distance from the end, whereby the end will operate after the manner of a hinge and fold over the end as shown in Fig. 2.

To hold the file in extended position a pivoted member 20 may be provided having parallel sides 21 and 22 adapted to fit opposite sides of the material and prevent bending along the crease 16'.

Suitable indexing printing may be provided for the front strip, whereby when it is set up on the shelf, the contents may be indicated by the front thereof. In order to provide means for changing the indexing 80 printing, a removable label member 23 is provided having the ends extending through and held within slits 24 and 25 in the front 14.

In the form shown in Figs. 1 and 2, a cover 17 is provided connected to the upper 85 edge of the side 11 and folding over the top and being connected to the side 10 by means of a suitable string fastener 18.

In the form shown in Fig. 3, the cover is omitted and the file is provided with an 90 indexing tab 19 such as commonly employed in vertical filing systems.

In case it should be desired to hold the file open for the convenient reception of the documents or other reason, a stiffening strip 95 20^a is provided, of equal width to the length of the file, whereby the same, when inserted in the bottom, will hold the file open, as shown in Fig. 6, and at the same time, reinforce the bottom and give rigidity to the 100 file as a whole.

As shown in Fig. 4 the rear end 21 of the file may be formed similarly to the front end 16.

As many changes could be made in the 105 above construction, and many apparently widely different embodiments of my invention, within the scope of the claims, could be made without departing from the spirit or scope thereof, it is intended that all mat- 110

ter contained in the accompanying specifications and drawings, shall be interpreted as illustrative and not in a limiting sense.

What I claim as my invention is:

- 5 1. A vertical file including an envelop formed with parallel sides, collapsible ends and bottom, the front end being formed with a flat strip adapted to receive indexing printing, being hinged to one side and adapted to fold over the opposite side.
- 10 2. A vertical file formed with an envelop having parallel sides and bottom formed with a bellows hinge, collapsible front and rear ends, the front end being formed with a strip of material hinged to one end and adapted to fold over the opposite end.
- 15 3. A vertical file including an envelop formed with parallel sides, collapsible ends and bottom, the front end being formed with a flat strip adapted to receive indexing printing, being hinged to one side and adapted to fold over the opposite side, a top cover for the file and means for fastening the same in closed position.
- 20 4. A vertical file formed of an envelop with parallel stiff sides, collapsible members connecting the sides along three edges, one at least of said collapsible members being formed with a flat strip adapted to receive

indexing printing, the said strip being 30 adapted to fold over the side.

5. A file having parallel sides and an end member, one of the sides being formed with a crease near the end member, adapted to permit the end member to fold over the side 35 and means on the side to hold the end member in extended position and prevent bending along the crease.

6. A file formed with parallel side members and an end member extending at substantially right angles thereto, and being hinged at one side, and being adapted, in collapsed position, to be bent into substantially the same plane as the sides, and means 40 for holding the end in extended position.

7. A vertical file comprising an envelop having stiff sides and an end member, one of the sides being formed with a crease near the end member, and a pivoted member on the side having parallel sides adapted to fold 45 over the line of crease, and prevent bending along the same.

In witness whereof I have hereunto set my hand in the presence of two witnesses.

PETER MacGREGOR.
